UNITED STATES PATENT OFFICE.

ABE LOUIS COHEN, OF MILWAUKEE, WISCONSIN.

STORM SUIT.

Application filed April 28, 1924. Serial No. 709,567.

To all whom it may concern:

Be it known that I, ABE LOUIS COHEN, a citizen of the United States, and resident of Milwaukee, in the county of Milwaukee and 5 State of Wisconsin, have invented certain new and useful Improvements in Storm Suits; and I do hereby declare that the following is a full, clear, and exact description thereof.

10 This invention relates to storm suits.

Objects of this invention are to provide a storm suit which will fully protect the wearer from the entrance of rain, which is so constructed that different degrees of protection may be afforded, and different degrees of freedom of movement accorded the user, and which is so designed that it will stand rough service.

Further objects are to provide a storm 20 suit which, although formed of water proof material and principally with cemented seams, is so reinforced that tearing of the seams most subjected to wear is prevented, and to provide a garment which may be 25 simply and cheaply manufactured.

An embodiment of the invention is shown in the accompanying drawings, in which:—

Figure 1 is a front view of the garment partly broken away showing it upon a wearer and in one position of adjustment.

Figure 2 is a rear view of the pants portion or leg portion, and with a part of the front panels.

Figure 3 is a view of the garment opened 35 out flat and with one of the front panels turned inwardly.

Figure 4 is a sectional view on the line 4—4 of Figure 3.

The garment comprises essentially a cape 40 portion 1 having a collar portion 2 and a pair of tubular leg portions 3 and 4 connected with the remaining portions of the garment by upwardly extending front panels 5 and 6.

45 The collar portion 2, it will be noted from Figures 3 and 4, is composed of a pair of plies which may be a single piece of material folded along its outer or uppermost edge. The lower edges of the plies forming

50 the collar overlap the cape 1 and the front panels 5 and 6 and are cemented thereto. It is to be noted, however, that the front panels 5 and 6 extend to the outermost edges of the collar while the union between 55 the cape portion and the collar stops short of the outermost edges of the collar portion

so as to provide freedom for the upper edges of the cape. Normally the collar is turned down and overhangs the garment, as shown in Figure 1. It is to be particularly noted from Figure 3 that at the point where the cape leaves the collar portion bar stitching 7 is employed and passes through the several layers, namely, the front panels, the cape portion and the collar portion, thus securely attaching the parts by means independent of the cemented seam and preventing tearing or opening of the seam. One of the front panels is provided with a button carrying fly 8 and the other front panel is provided with a plurality of button holes 9 adapted to receive the button so that these panels will form in effect a vest like portion immediately rearward of the front opening of the cape.

The cape in its most completely closed position is adapted to have the button holes 10 attached to the buttons 11 to thus completely close the garment. However, when this extreme protection is not needed the cape may be left open and the vest like portion formed by the front panels will sufficiently protect the wearer.

In order to hold the cape portion inwardly against the body of the wearer under certain conditions, a pair of tabs or straps 12 and 13 are provided upon the inner sides of the cape adjacent the hip portions and are adapted to detachably engage buttons 14 carried by the rear portions of the front panels, as may be seen from Figure 3. When, however, it is desired to have the cape open and also to have a material degree of freedom, these straps are unbuttoned and thus the cape is left free of attachment from other portions of the garment except at the collar portion. The curved rear edges 15 (see Figure 3) of the front panels secures accurate conformation of the garment to the body and prevents binding.

It is to be further noted that under certain conditions the cape may be unbuttoned all of the way to the top and may be turned back to the point of the bar stitching 7 to provide maximum freedom for the user.

If desired, foot straps or loops 16 may be carried by the lower ends of the tubular leg portions to retain them in their correct position. It is also to be noted that, if desired, arm straps 17 may be provided upon the inner side of the caps adjacent its for-

ward edges, such arm straps being employed in their usual capacity.

It will thus be seen that a storm suit has been provided which will afford maximum freedom to the wearer under all conditions, and which is adapted for various adjustments or conditions of wear.

It will further be seen that the garment may be cheaply manufactured and will not 10 be readily torn or distorted even under hard usage as the maximum freedom from binding or stresses is secured.

Although the invention has been described in considerable detail, it is to be understood that the invention may be variously embodied and is, therefore, to be limited 15 only as claimed.

For example while I have shown a cape as the upper part of the garment, obviously, 20 I may substitute therefor a jacket or vest with or without sleeves.

I claim:

1. A waterproof storm suit comprising a garment having a neck portion and having 25 front flies, a pair of tubular leg portions, and front panels adapted to be secured together and forming continuations of the leg portions, said front panels being secured to said cape adjacent the neck portion.

2. A waterproof storm suit comprising 30 a cape having a collar portion folded over its upper edge, a pair of tubular leg portions, and extension panels projecting upwardly from said leg portions and secured 35 beneath the collar portion, said panels hav-

ing interengaging fastening means upon adjacent edges and adapted to form a front body portion, and said cape having a front opening located exteriorly of said panels.

3. A storm suit comprising a cape having 40 front flies provided with interengaging fastening means, a collar secured to said cape, a pair of tubular leg portions having front panels extending upwardly and secured to said collar and adapted to be joined 45 along adjacent inner edges, and straps secured to the inner side of said cape and detachably attached to said panels adjacent the outer edges of such panels.

4. A storm suit of waterproof material 50 comprising a cape, a collar portion formed of double ply construction with the neck portion of said cape cemented between the plies to points spaced inwardly from the ends of the neck portion of the cape, a pair 55 of tubular leg members having upwardly extending front, vest like panels adapted to be secured together, the upper ends of said panels being cemented between the plies of the collar portion and extending to the ends 60 of the collar portion, and bar stitching passing through the collar portion, the cape and the upper ends of the panels at the said spaced points of said cape.

In testimony that I claim the foregoing 65 I have hereunto set my hand at Milwaukee, in the county of Milwaukee and State of Wisconsin.

ABE LOUIS COHEN.
